UNITED STATES PATENT OFFICE.

WILLIAM RENNYSON, OF NORRISTOWN, PENNSYLVANIA.

TYPE-WRITING MACHINE.

SPECIFICATION forming part of Letters Patent No. 451,573, dated May 5, 1891.

Application filed November 25, 1890. Serial No. 372,582. (No model.)

To all whom it may concern:

Be it known that I, WILLIAM RENNYSON, a citizen of the United States, residing at Norristown, in the county of Montgomery and 5 State of Pennsylvania, have invented certain new and useful Improvements in Type-Writing Machines, of which the following is a specification, reference being had therein to the accompanying drawings, in which—

10 Figure 1 represents a side elevation of a funnel-shaped cup provided with my improved directrix; Fig. 2, a bottom view thereof; and Figs. 3 and 4, respectively, sectional and bottom views of the device attached to the 15 guide-opening of an ordinary type-writer.

The invention is particularly designed for employment in connection with my former patent, numbered 403,075, dated May 7, 1889, in which a funnel-shaped cup is employed to 20 guide the type-bars to their proper point upon the impression-surface; but it may with equal advantage be applied to any machine wherein pivoted type-bars are used, and it is necessary that all the bars be guided without 25 injury to their printing-characters to a certain point upon the impression-surface, as will be more fully hereinafter set forth.

The invention has for its object the provision of an extremely simple device for accurately guiding the type-bars to their proper point upon the impression-surface; and it 30 consists of a series of radially-arranged laterally-yielding springs or sections applied to an opening in a support held in close proximity to the printing-surface, whereby the type-bars will all be accurately guided to the same point and all wear of the type-bars or 35 springs compensated for, and whereby different-sized type-bars may be accommodated, as 40 will presently appear.

In the drawings, *a* designates a funnel, which is supported in any suitable manner in close proximity to the printing-surface, and which may be arranged, as shown, to 45 print upon a matrix or surface below, or it may be inverted when it is desired to print upon a surface arranged above it. Secured to the inclined exterior of this cup are a plurality of springs *b*, (preferably four,) which 50 are arranged radially with respect to the smaller opening of the funnel, and which extend over the opening and terminate equal

distances from its center. The inner ends of the springs preferably do not touch each other; but they may be adjusted to contact 55 with each other, if desired. The springs are secured adjustably to their support by means of slats and screws in order that they may be accurately adjusted with respect to the center of the opening to which they are applied, 60 and also in order that they may be adjusted at intervals to compensate for wear of the parts.

The yielding sections may be applied with equal advantage to the guide-openings of 65 the ordinary type-writing machines, as shown in Figs. 3 and 4. In these figures the springs are shown adjustably secured to the under side of the support *a'*, and bent or turned up into the opening therein a suitable distance. 70 The support *a'* may be secured to the frame of the machine in any suitable manner.

The advantages of this manner of guiding the type-bars are obvious. The yielding sections will accommodate various-sized type-bars and guide them all to the proper point upon the impression-surface, thereby keeping the characters in perfect alignment, whether the type-bars all be of the same size or not. 75 This feature of adapting itself to type-bars of different shapes and sizes is important in that it will not be necessary hereafter to get all the bars exactly the same size, and it is also advantageous for the reason that some of the type-bars, being used more than others, become worn and reduced in diameter and would therefore be too small for the guide-opening if some means were not provided to compensate for such wear. It is also obvious that wear and friction will be reduced to a 80 minimum by employing these yielding sections, and also that there will be less danger of injury to the type or characters.

Inasmuch as the feature of the invention is to provide a yielding and variable guide-opening for the type-bars, it is obvious that the arrangement of the springs may be varied without departing from the invention. 95 For instance, one of the springs or sections may be made rigid, if desired, in order to insure the perfect alignment of the letters.

I am aware that it is not new to arrange around a type-opening a series of radial pivoted dogs for the purpose of centering the

type, and therefore do not broadly claim such construction.

The peculiar advantage of my rigidly-se cured springs is that said springs serve to 5 positively guide the type to the proper point and at the same time yield sufficiently laterally to readily accommodate type of different sizes. Furthermore, there are no pivots to 10 wear loose, and the elastic sections may be readily adjusted with respect to the center of 15 the guide-opening to compensate for wear and to properly center the type.

Having thus fully described my invention, what I claim is—

15 1. The combination of a support having an opening for the passage of the type-bars, and a series of radially-arranged springs rigidly secured to the said support and having their free ends extending to near the center of the 20 said type-opening in the support, substantially as described.

2. The combination, with a support provided with an opening for the passage of the type-bars, of a directrix consisting of a series 25 of radially-arranged sections rigidly secured to the said support and having their free ends

terminating nearly in line with the center of the said type-opening, one or more of the said sections being elastic at its free end, as and for the purposes described.

3. The combination, with a support having an opening for the passage of the type-bars, of a directrix consisting of a series of radially-arranged sections rigidly and adjustably secured to the said support and having their 35 free ends terminating nearly in line with the center of the said opening, one or more of the sections being adapted to yield at its free end, substantially as described.

4. The combination, with a funnel provided 40 with a guide-opening for the type-bars, of a series of radially-arranged springs adjustably secured to the smaller end of the same and having their free ends terminating nearly in line with the guide-opening, substantially 45 as described.

In testimony whereof I affix my signature in presence of two witnesses.

WILLIAM RENNYSON.
